UNITED STATES PATENT OFFICE.

WILLIAM PAUL STARKEY, OF HARRISBURG, PENNSYLVANIA, ASSIGNOR TO THOMAS E. MARTIN, OF BUFFALO, NEW YORK.

MECHANICAL STOKER.

1,077,494.

Specification of Letters Patent.

Patented Nov. 4, 1913.

Application filed November 19, 1908. Serial No. 463,488.

To all whom it may concern:

Be it known that I, WILLIAM P. STARKEY, a citizen of the United States of America, and resident of Harrisburg, in the county of Dauphin and State of Pennsylvania, have invented certain new and useful Improvements in Mechanical Stokers, of which the following is a specification.

This invention relates to improvements in mechanical stokers and more particularly to that class of stokers which are provided with a revolving type of grate.

The objects of my invention are to devise a stoker in which the revolving rollers rotate varying amounts so that the roller nearest the feed hopper may revolve a greater amount than the one nearest the foot of the stoker, and also to provide other improvements which will be hereinafter noted.

The invention in its preferable embodiment consists of the construction hereinafter described and then claimed.

In the drawings accompanying and forming part hereof: Figure 1 is a vertical longitudinal section of part of a furnace having my improvement applied thereto. Fig. 2 is an end elevation of the same, partly in section. Fig. 3 is a side elevation, partly in section, of one of the diagonally arranged side frames which support the various revolving grates. Fig. 4 is a vertical section through one of the ratchet drives. Fig. 5 is a sectional detail of part of the adjusting mechanism for the ratchet drives. Fig. 6 is a vertical section of two of the grate rollers showing the stationary grate bars in connection therewith. Fig. 7 is a longitudinal section of part of one of the grate rollers. Fig. 8 is a detail of one of the roller heads. Fig. 9 is a detail showing a section of the journaled support for the stationary grate bar and a top plan view of its journaled end. Fig. 10 is a sectional detail of one of the stationary grate bars.

Referring now to the details of the drawings by numerals: 1 designates a hopper which may be of any desirable shape and construction into which the coal is fed and coating with one side of which is a feed gate 3 adapted to be raised and lowered in any approved manner to fix the thickness of coal passed into the furnace, the same as in any ordinary stoker. At the lower end of the stoker I also employ an ash plate 4 piv-

totally supported at 5 and which is adapted to be opened and closed by means of the lever 6, the front end of which is provided with a handle 7 and is notched at 8 to coact with a hanger 9 so that the ash plate 4 may be adjusted to any desirable position; said ash plate discharging into a pit 10 under it and the rollers. Between the hopper 1 and the ash plate 4 are supported diagonally disposed side frames 12, one on each side of the furnace, and these two diagonally disposed side frames 12 support the revolving rollers 14, which, as illustrated in my drawings, I prefer to have six in number. These rollers 14 are made up of a number of segments which in reality form disks, there being four segments to complete the circumference. These rollers will be hereinafter more particularly described in detail and it will now be sufficient to state that they are fastened to and revolve with a shaft 16 capable of rotation in bearings 17 of the aforesaid diagonally disposed side frames 12, it being understood that there is one shaft 16 for each set of the six sets of rollers. The aforesaid six sets of revolving rollers 14 occupy substantially all the space between the hopper 1 and the ash plate 4 except for the small spaces between the various sets of rollers, and these spaces are filled by means of non-rotatable grate bars 18 of the particular shape shown in Fig. 6. These grate bars 18 are secured to supports 19 which supports are journaled or trunnioned in U-shaped hangers 20 shown in Fig. 3; and the supports 19 are counterbalanced by means of a weighted lever 21 which causes the grate bars 18 and their supports 19 to move on their journals or trunnions 22 so that the point of the grate bars 18 will hug the sections of the rollers 14 as clearly indicated in Fig. 6. It will be observed that the non-rotatable grate bars 18 have suitable spaces formed in them in which water may be circulated in any desirable way to prevent them from burning and the rollers 14 are also formed in a particular way to prevent burning and this construction will now be described. Each of the six rollers is formed of a series of heads 23 and each pair of these heads is connected by a series of rods 24 and on each of these rods is a series of preferably six segments 25 pivotally secured to the rods and spaced apart by means of separators 26.

The aforesaid segments 25 are pivotally secured on the rods 24 so that when the rollers are in position the various segments will assume the positions shown in Fig. 6 where-
 5 in it will be observed that the lowest sections, after passing the non-rotatable grate bars 18, are permitted to drop by gravity thus making an opening at the bottom of the roller which makes it possible for the roller to clean itself since the ashes or fine par-
 10 ticles which find their way between the segments of the rollers are permitted to fall out of the opening formed by the dropping down of the grate segments as shown in
 15 said Fig. 6. Moreover, since the rods 24 are held in position by means of a cotter as 27 it will be observed that any of the segments may be removed by taking out the cotter and sliding the proper rod 24, this
 20 being permitted by moving the next segments upward so as to allow of the rod 24 being moved longitudinally out of its bearings and its segments.

Referring now once more to the non-rotatable grate bars 18 it will be observed that these are slantingly disposed so as to pass the fuel from a high point on one roller to a lower point on the succeeding roller, the fuel thus being assisted in its passage from
 30 one roller to the other.

Each of the aforesaid shafts 16, to which the aforesaid rollers 14 are secured, has secured to one of its ends a ratchet wheel 15 which is keyed to the said shaft. In order
 35 to give these ratchet wheels movement, and therefore impart rotary movement to the revolving rollers 14, I employ cranks 26 and 28 which receive an oscillating motion from any exterior source of power (not shown)
 40 and to the crank 28 are connected two bars 30 and between these bars are pivoted a series of pawls 32, there being one pawl for each ratchet wheel, and the pawls are provided with weighted tails 33 which, by
 45 gravity, keep the pawls in contact with the wheels. It follows from this construction that when the cranks 26 and 28 are oscillated, the bars 30 are given a reciprocating motion in such a manner that when the bars
 50 30 are moved to the left as shown in Fig. 5, the pawls engage and rotate said ratchet wheels 15 and therefore rotate the revolving rollers and when the rods 30 are reciprocated in a reverse direction the pawls slip
 55 over the ratchet teeth in a manner well understood. For a purpose to be hereinafter described, I prefer to give these ratchet wheels differential movement in order to give the rollers different amounts of rotation.
 60 To this end I arrange a curved plate 38 in close proximity to each ratchet wheel, this curved plate 38 being held between two castings 40 and 41 arranged on opposite sides of the ratchet wheel. Each pair of castings
 65 40 and 41 contains a pair of grooves 42

within which works a pin 44 and the pin of each ratchet wheel is connected to a separate lever 46. There are, therefore, six levers as shown in Fig. 4 and each of these levers 46 has a handle 47 and teeth 48, the latter en-
 70 gaging with a holding plate or catch 50, shown in Fig. 5. The construction is such that when the levers 46 are moved by an operator catching hold of the handle 47 and giving any one of said levers 46 reciprocating movement, one set of the castings 40 and 41 receives oscillating movement on its
 75 shaft 16 and this oscillation of course moves to a small extent the curved plate 38. Inasmuch as each of the six levers 46 may be moved independently of the others, it follows that each set of the castings 40 and 41 and each of the curved plates 38 may thus be adjusted independently of the others. The purpose of this is to adjust the curved
 80 plates 38 with respect to the pawls 32. It is my purpose to provide a differential feed and to do so I prefer to adjust the ratchet drives so as to, for example, give one-twelfth of a revolution per minute to the
 85 roller nearest the hopper 1 and to give to the roller nearest the ash plate one one-hundred-and-twentieth revolution per minute and to have the others operating at velocities between these two speeds. Therefore
 90 the attendant adjusts the levers 46 so that the curved plate 38 of the ratchet wheel nearest the hopper 1 will expose a larger number of teeth to the action of its pawl 32 than the others. The appropriate lever 46
 95 for the second ratchet wheel will be adjusted so that its curved plate 38 will expose, say, one less tooth, and the other four levers 46 are also adjusted so as to respectively expose, say, one less tooth of each ratchet
 100 wheel, so that the last ratchet wheel, the one nearest the ash plate 4, will revolve a smaller distance than the roller nearest the hopper 1.

The operation of my stoker is as follows: Coal is fed into the hopper 1 and as the rollers revolve, the coal is carried over the first roller and slides down over the slanting stationary grate 18 to the second set of rollers and so on down over the six sets of rollers until it passes over the last one where it is deposited on the ash plate 4 or fed through between the last roller and said ash plate 4 into the ash pit 10 below. By means of the adjustable ratchet drive, I propose to rotate the first roller, say, one-twelfth of a revolution per minute and the last roller at one one-hundred-and-twentieth revolution per minute or one revolution in two hours. My purpose is to pass the coal over the first roller approximately three inches thick and by the time it reaches the sixth roller the ashes will be approximately 8 to 10 inches thick and the depth of the bed in between these rollers will vary from

three inches at the top to about 10 inches at the bottom. The variation of the speed of the stoker from one-twelfth of a revolution per minute to one one-hundred-and-twentieth revolution per minute is a feature I consider of great importance.

Another feature I consider of importance is the arrangement hereinbefore described of the last roller of the series of rollers 14 10 and the ash plate 4 pivotally supported adjacent to said roller. The revolving roller working in connection with said ash plate makes an excellent combination since the ash plate may be set at the proper position 15 to deliver the ashes continuously thus doing away with the dumping idea which prevails in many stokers causing a loss of coke into the ash pit and a land slide of coal on the fall, thereby decreasing the efficiency of the 20 stoker.

From the foregoing description and the accompanying drawings, it will be seen that I have invented a mechanical stoker of the roller type which may be given a differential feed under the easy control of an attendant. It is obvious that modifications and changes may be made without departing from the spirit of my invention, the scope of which is set forth by the appended 25 claims.

What I claim as my invention is:

1. In a device of the character described, a series of rotatable cylindrical grates, means for supporting said grates alongside 35 of each other, means common to all of said grates for rotating the same, said means comprising ratchet wheels and pawls engaging said wheels, and independently adjustable means for varying the duration of 40 the engagement of each pawl with its respective ratchet wheel, whereby each pawl turns its ratchet wheel farther than the next succeeding pawl turns its ratchet wheel, substantially as described.

45 2. In a fuel feeding grate, the combination of a series of fuel supporting members, cylindrical in shape and extending across the furnace, said members having substantially the same diameter and each having 50 fuel supporting surfaces and ash discharge and air supply openings, and means common to all of said grate members for rotating the same, said means adapted to so rotate the grate members as to produce a gradually 55 decreasing feeding action upon the fuel from the front to the rear of the grate, substantially as described.

3. In a fuel feeding grate, the combination of a series of transversely arranged 60 cylindrical grate members, non-rotatable grate bars arranged between the said grate members, said bars adapted to feed fuel from a high point on one adjacent grate member to a relatively low point on the next 65 succeeding grate member, and means for ro-

tating the cylindrical members to progressively feed the fuel from the front to the rear of the grate, substantially as described.

4. In a device of the character described, a series of rotary grates, a ratchet wheel for 70 each grate, a pawl carrier adapted to co-act with said ratchet wheels to rotate said wheels and their grates, and a curved shield or plate for each ratchet wheel, said curved shields being independently adjustable to 75 control the amount of rotation of the same, substantially as described.

5. In a device of the character described, a series of rotary grates, a ratchet wheel for 80 each grate, a pawl carrier having pawls co-acting with said ratchet wheels to rotate said wheels and their grates, a curved shield or plate for each ratchet wheel, said shields being independently adjustable to 85 control the amount of rotation of the ratchet wheels, and a series of levers for controlling the position of said curved shields or plates, substantially as described.

6. In a device of the character described, a series of rotary grates, a shaft for each 90 grate, a ratchet wheel for each shaft, a pawl for each ratchet wheel, and a curved plate or shield for each ratchet wheel adapted to be rotated between said pawl and said ratchet wheel, each curved plate or shield 95 being independently adjustable, and a lever for operating each curved plate or shield, said pawl and ratchet mechanisms being connected to operate in unison whereby the movement of each grate may be independently adjusted, substantially as described.

7. In a device of the character described, a series of rotary grates, a ratchet wheel for 100 each grate, a pawl for each ratchet wheel, a pair of side members carrying a curved shield or guide adjacent to each ratchet wheel, each curved shield or guide being independently adjustable, and a lever for operating said side members, said pawl and ratchet mechanisms being connected to operate in unison whereby the movement of each grate may be independently adjusted, 105 substantially as described.

8. In a device of the character described, a series of rotary grates, a ratchet wheel for 110 each grate, a pawl carrier having a series of pawls co-acting with said ratchet wheels, means for giving said pawl carrier reciprocating movement, and curved plates or shields located adjacent to said ratchet 115 wheels and said pawls, and levers for independently adjusting said curved plates or shields, substantially as described.

9. In a device of the character described, a series of rotary cylindrical grates, and a 125 series of non-rotatable grate bars interposed between said cylindrical grates, said non-rotatable grate bars being journaled or trunnioned and feeding the fuel from a high point on one adjacent cylindrical grate to a 130

relatively low point on the next succeeding cylindrical grate, the fuel being fed progressively from the front to the rear of the grate, substantially as described.

- 5 10. In a device of the character described, a series of rotatable cylindrical grates, and a series of non-rotatable grate bars interposed between said cylindrical grates, said non-rotatable grate bars being journaled or 10 trunnioned and feeding the fuel from a high point on one adjacent cylindrical grate to a relatively low point on the next succeeding cylindrical grate, means for counter-balancing said slanting grates to position them 15 with respect to said cylindrical grates, and means for rotating the cylindrical members to progressively feed the fuel from the front to the rear of the grates, substantially as described.
- 20 11. In a device of the character described, a feed hopper, an ash gate, a series of rotary grates arranged between said hopper and said ash gate, a ratchet wheel for rotating each of said grates, pawls co-acting with said 25 ratchet wheels, curved plates or shields co-acting with said ratchet wheels, and independently movable levers for controlling the positions of said curved plates or shields, said pawl and ratchet mechanisms being connected to operate in unison with respect to 30 said shields, whereby the movement of each grate may be independently adjusted, substantially as described.
12. In a device of the character described, 35 a roller grate comprising a body portion and a series of segmental sections pivotally mounted to form a roller, said sections dropping by gravity as the sections reach the bottom, substantially as described.
- 40 13. In a device of the character described,

a roller grate comprising a body portion and a series of segmental sections pivotally mounted to form a roller, said sections dropping by gravity as the sections reach the bottom, and said sections being staggered with 45 relation to each other, substantially as described.

14. In a device of the character described, a roller grate comprising a shaft, heads secured thereto, bars connecting said heads, and segmental sections pivotally supported by said bars and forming the periphery of the roller, each section dropping by gravity as it reaches the bottom, substantially as described. 55

15. In a device of the character described, a roller grate comprising a shaft, heads secured thereto, bars connecting said heads, and segmental sections pivotally supported by said bars and forming the periphery of 60 the roller, each section dropping by gravity as it reaches the bottom, said bars and said sections being staggered with relation to each other, substantially as described.

16. A horizontal rotary grate member cylindrical in shape comprising a series of movably mounted grate bars pivotally arranged about the axis of rotation of said member, the respective bars of said series adapted to swing outwardly while occupying 70 a lowered position on said member, so as to permit the discharge of ashes from said member, substantially as described. 65

Signed by me at Harrisburg this 16th day of November 1908.

WILLIAM PAUL STARKEY.
